UNITED STATES PATENT OFFICE.

GEORGE F. GARRITY, OF SCRANTON, PENNSYLVANIA.

SPRING.

Specification of Letters Patent. Patented May 25, 1915.

1,140,455.

Application filed October 26, 1914. Serial No. 868,712.

To all whom it may concern:

Be it known that I, GEORGE F. GARRITY, a citizen of the United States, residing at Scranton, in the county of Lackawanna and State of Pennsylvania, have invented certain new and useful Improvements in Springs, of which the following is a specification, reference being had to the accompanying drawings.

10 This invention relates to certain improvements in springs and has relation more particularly to a spring especially designed and adapted for use in connection with railroad rolling stock; and an object of the invention is to provide a device of this general character of novel and improved construction whereby a maximum of tension is possessed is a spring produced from a minimum of material.

20 Furthermore, it is an object of my invention to provide a novel and improved spring of this general character which may be produced with a minimum of cost and comprising a plurality of superimposed blades, the 25 adjacent faces of which being in contact one with the other and wherein the means for increasing the tension of each of the blades of the spring also serves as a medium for preventing the blades from moving laterally 30 one independently of the other whereby the balance of the spring would be materially affected.

The invention consists in the details of construction and in the combination and arrangement of the several parts of my improved spring whereby certain important advantages are attained and the device is rendered simpler, less expensive and otherwise more convenient and advantageous for 40 use, all as will be hereinafter more fully set forth.

The novel features of the invention will be carefully defined in the appended claims.

In order that my invention may be the 45 better understood, I will now proceed to describe the same with reference to the accompanying drawings, wherein—

Figure 1 is a side elevational view of a spring constructed in accordance with an embodiment of my invention; and Fig. 2 is 50 a sectional view taken substantially on the line 2—2 of Fig. 1.

As disclosed in the accompanying drawings, S denotes a spring constructed in accordance with an embodiment of my invention and which is especially adapted to be

employed in connection with railroad rolling stock and particularly locomotives and, as herein set forth, said spring comprises a plurality of superimposed blades B tied at 60 substantially their longitudinal centers by a clamp C of conventional construction.

As herein disclosed, the blades B are of identical transverse diameter and each of said blades has produced in its longitudinal 65 marginal portions and equidistantly spaced relative to the transverse center thereof the shallow depressions 1 which are preferably produced in the blade by roller pressure whereby it is assured that the opposite surfaces of the blade are each in absolute continuity and no abrupt or angular portions are afforded which would obstruct such surfaces, as it will be at once apparent that should the surfaces of said springs be provided with any angular portions the flexure 70 of the blade, when in use, would have a tendency to occur at such points and which in practice has been found to materially reduce the efficiency of the spring. It is also to be 75 observed that each of the depressions in cross section is disposed on the same curvature whereby the depths of the depressions and their transverse diameters will be identical. The thickness of each of the blades B 80 is identical at all points whereby the proper balance of the spring is further assured. It is also essential to the successful operation of my invention, as herein embodied, that the 85 depressions 1 be disposed in parallelism with the longitudinal edges of each of the blades and with each other and directed entirely along the blade and that the portion of the blade intermediate the depressions should be straight in cross section. It will also be 90 readily observed that the balance of the spring is further materially enhanced by having the depressions 1 equidistantly spaced relative to the transverse center of 95 the blades. It is also to be observed that 100 when the blades B are in applied position one relative to the other, the opposed faces thereof are in contact at all points and that the depressions 1 also effectively serve to hold said blades against any relative transverse movement which would offset the balance of the springs and thus affect in a large degree the efficiency of the device.

105 From the foregoing description, it is thought to be obvious that a spring constructed in accordance with my invention is 110 of an extremely simple and comparatively

inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement 10 and formation of the several parts herein shown in carrying out my invention in practice.

I claim:

1. A spring of the character described 15 comprising an elongated member having longitudinal depressions disposed therein and extending entirely therealong, said depressions being adjacent the longitudinal marginal portions of the member and equidistantly spaced relative to the transverse center thereof, the opposed faces of the member being in continuity and being free and unobstructed, said member being of the same thickness at all points, the portion of 20 the member intermediate the depressions being straight in cross section.

2. A spring of the character described 30 comprising a plurality of superimposed blades, each of said blades being provided adjacent its longitudinal marginal portions with depressions therein disposed longitudinally thereof and entirely therealong, said depressions being parallel with the longitudinal edges of the blades and with each 35 other and equidistantly spaced from the transverse center of the blade, the portion of the member intermediate the depressions being straight in cross section.

3. A spring of the character described 40 comprising a plurality of superimposed

blades, each of said blades being provided adjacent its longitudinal marginal portions with depressions therein disposed longitudinally thereof and entirely therealong, said depressions being parallel with the longitudinal edges of the blades and with each other and equidistantly spaced from the transverse center of the blade, the portion of the member intermediate the depressions being straight in cross section, the opposed 45 faces of the blades being in contact one with the other at all points, the interlocking of the depressions of the blades serving to hold such blades against relative transverse movement, and means at substantially the longitudinal center of the blades for holding the 50 same in assembled relation.

4. A spring of the character described 55 comprising an elongated member having longitudinal depressions disposed therein and extending entirely therealong, said depressions being adjacent the longitudinal marginal portions of the member and equidistantly spaced relative to the transverse center thereof, the opposed faces of the 60 member being in continuity and being free and unobstructed, said member being of the same thickness at all points, said depressions being disposed on the same curvatures whereby the depths and transverse diameters thereof are identical, the portion of 65 the member intermediate the depressions being straight in cross section.

In testimony whereof I hereunto affix my signature in the presence of two witnesses. 75

GEORGE F. GARRITY.
